US0D1093076S

(12) **United States Design Patent** (10) **Patent No.:** **US D1,093,076 S**
(45) **Date of Patent:** **** Sep. 16, 2025**

(54) **CONTAINER**

(71) Applicant: **Runway Blue, LLC**, Alpine, UT (US)

(72) Inventors: **John R. Omdahl, II**, Lindon, UT (US);
David O. Meyers, Layton, UT (US)

(73) Assignee: **Runway Blue, LLC**, Lehi, UT (US)

(**) Term: **15 Years**

(21) Appl. No.: **29/874,599**

(22) Filed: **Apr. 21, 2023**

Related U.S. Application Data

(63) Continuation of application No. 29/703,415, filed on Aug. 27, 2019, now Pat. No. Des. 988,787.

(51) **LOC (15) Cl.** **07-02**

(57) **CLAIM**

The ornamental design for a container as shown and described.

DESCRIPTION

FIG. 1 is a top front perspective view of a container showing the claimed design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the figures show portions of the container that form no part of the claimed design.

1 Claim, 7 Drawing Sheets
